UNITED STATES PATENT OFFICE.

JOHN ALBERT STRAUB, OF MUSKEGON, MICHIGAN.

DESIGN FOR A COMBINATION TRAY, PENRACK, AND INKWELL.

Application filed October 18, 1922. Serial No. 4,016. Term of patent 14 years.

To all whom it may concern:

Be it known that I, JOHN ALBERT STRAUB, a citizen of the United States of America, residing at Muskegon, in the county of Muskegon and State of Michigan, have invented a new, original, and ornamental Design for Combination Tray, Penrack, and Inkwell, of which the following is a specification, reference being had to the accompanying drawings forming a part hereof.

The figure is a perspective view of a combination tray, pen rack, and ink well showing my new design.

I claim:—

The ornamental design for combination tray, penrack and inkwell as shown.

JOHN ALBERT STRAUB.
